POULTRY NECK CUTTER

Edward K. Leffler, West Allis, and Kenneth A. Kraft
and Calvin Hansen, Milwaukee, Wis., assignors to John
Mohr & Sons, Milwaukee, Wis.

Filed Feb. 1, 1971, Ser. No. 111,214

Term of patent 14 years

Int. Cl. D15—08

U.S. Cl. D11—1

FIG. 1

FIG. 2

FIG. 3

FIG. 4

FIG.5

FIG. 6

FIG. 1 is a top plan view of the poultry neck cutter embodying our design;

FIG. 2 is a bottom plan view thereof;

FIG. 3 is a side elevational view thereof;

FIG. 4 is a side elevational view thereof showing the opposite side of the poultry neck cutter;

FIG. 5 is a front elevational view thereof; and

FIG. 6 is a rear elevational view thereof.

We claim:

The original design for a poultry neck cutter, as shown.
